U.S. PATENT DOCUMENTS

The ornamental design for a cigarette extinguishing plate for an ashtray receptacle, as shown and described.

DESCRIPTION

FIG. 1 is a front perspective view of a cigarette extinguishing plate, according to an embodiment of the invention.

FIG. 2 is a top view of the cigarette extinguishing plate shown in FIG. 1.

FIG. 3 is a rear view of the cigarette extinguishing plate shown in FIG. 1.

FIG. 4 is a right side view of the cigarette extinguishing plate shown in FIG. 1, which is identical to the left side view; and, FIG. 5 is a bottom view of the cigarette extinguishing plate shown in FIG. 1.

The broken lines are shown for illustrative purposes only and form no part of the claimed design.
